(57) **CLAIM**

The ornamental design for an intermittent urinary catheter,
as shown and described.

DESCRIPTION

FIG. 1 is a perspective view of an intermittent urinary catheter.

FIG. 2 is a front plan view of the intermittent urinary catheter.

FIG. 3 is a back plan view of the intermittent urinary catheter.

FIG. 4 is a top side view of the intermittent urinary catheter, where a bottom side view is not provided as it is a mirror image of the top side view.

FIG. 5 is a left side view of the intermittent urinary catheter; and,

FIG. 6 is a right side view of the intermittent urinary catheter.

The broken lines showing a leading proximal end, and the
broken lines showing urine inlets, are included to illustrate
unclaimed portions of the intermittent urinary catheter and
form no part of the claimed design.

The catheter is shown with a symbolic break in its length.
The appearance of any portion of the article between the
break lines forms no part of the claimed design.
